ADVERTISING DEVICE

Eldred A. Boline, Denver, Colo.

Application December 29, 1939, Serial No. 311,441

9 Claims. (Cl. 40—36)

This invention relates to an advertising display device and has for its principal object the provision of a highly efficient mechanism which will successively display a series of advertising cards to produce a continuously changing display of advertisements, and which can be operated either by hand or by means of an electric motor.

Another object of the invention is to provide a motor operated device which cannot damage the cards or displays even though the machine may become clogged.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a perspective view of the improved advertising display device enclosed in a suitable ornamental housing.

Fig. 2 is a vertical section therethrough, taken on the line 2—2, Fig. 1.

Fig. 3 is a front view of a motor operated operating mechanism with the enclosing housing removed.

Fig. 4 is a vertical section through a hand operated form of the invention.

Figs. 5 to 8 inclusive, are diagrammatic views illustrating the operation of the card changing mechanism.

Fig. 9 is a fragmentary vertical section taken on the line 9—9, Fig. 4.

Fig. 10 is a detail section through the card changing mechanism, taken on the line 10—10, Fig. 7.

The operating mechanism is supported from a base plate 10 upon a vertical post 11 and a vertical guide 12. A pack of cards, illustrated at 13, carrying the advertising to be displayed, is carried in an inclined card holder 14 supported from the base plate upon suitable pedestals 15. A glass plate 33 covers the front of the card holder.

The device operates to continuously lift the lower or rearmost card of the pack and deposit the same on the front of the pack.

The changing of the cards is accomplished by means of a tubular slide 16 which rides vertically on the guide 12. The slide member 16 is lifted by means of a cross head 17 also slidably mounted on

the guide member 12. The cross head may be lifted either by hand or by a motor driven mechanism. For hand operation, a hand lever 18 is pivoted, as shown at 19 between the pedestals 15 and extends rearwardly through the guide 12 beneath the cross head 17. Thus, when the forward extremity of the lever is depressed, the rearward extremity thereof will act to lift the cross head and the tubular slide 16.

As the slide rises, the rearmost card of the pack 10 is pushed upwardly by frictional engagement with the edge of a rubber pushing block 22 which is supported from the tubular slide upon suitable leaf springs 23. A gripping plate 24, pivotally mounted upon a hinge clip 25 extending from the slide 16, carries an L-shaped weight 26 which bears on the cards ahead of the rearmost card to prevent the former from moving upwardly with the latter, as shown in Fig. 5. After the rearmost card has been pushed upwardly from the pack, the weight 26 will swing downwardly against the front thereof and the springs 23 will cause the block 22 to clamp the card thereagainst, as shown in Fig. 6. The slide continues to rise carrying the card with it until the card is clear of the pack, as shown in Fig. 7. On its way upward the gripping plate snaps beneath a ratchet extremity 27 on a releasing spring 28, as shown in Fig. 7.

The slide 16 now moves downwardly, as shown in Fig. 8, causing the gripping plate 24 to strike the extremity 27 of the releasing spring 28. As the slide continues downward the gripping plate is held so that the card is released and forced forward by the springs 23 to drop onto the front of the pack, as shown in Fig. 8. As the slide 16 continues downward, the gripping plate 24 snaps from position in the ratchet extremity 27 and again drops down on the top of the pack of cards, as shown in Fig. 5, to repeat the cycle of operation. The gripping plate carries a rubber contact cushion 42 to cushion its contact with the releasing spring 28.

Means are provided to adjust the device for various card thicknesses, and it can also be adjusted to pick up one or more cards, by means of an adjustable backing plate 29 which is supported on adjusting screws 30 from the back of the card holder 14. By adjusting the screws 30, the position of the rearmost card in relation to the lifting mechanism can be varied. The releasing spring 28 is suspended from a top frame member 31 having sockets 32 for receiving the upper extremities of the members 11 and 12.

Thus, it can be readily seen that if the slide 35

member 16 moves upwardly, it will first cause the block 22 to push the rearmost card above the other cards then the gripping lever 24 will swing downward to bring the weight 26 against the card to hold it against the block 22. As soon as the lower extremity of the lifted card passes above the pack of cards, it will snap forward to the position of Fig. 7 at which time the slide member will start downwardly. The first movement will release the weight 26 allowing the card to fall to the front of the pack.

In the motor driven form of the device, a connecting rod 34 is connected at its lower extremity with a pin 35 secured to the cross head 17. The upper extremity of the connecting rod is hingedly mounted on a crank pin 36 extending from a worm wheel 37. The worm wheel 37 is journaled on a suitable axle member 38 on the rear frame member 11 and is rotated from an electric motor 39 through the medium of a suitable transmission worm 40.

It is desired to call attention to the fact that the downward movement of the slide member 16 and its associated mechanism is accomplished by gravity only. There is no positive push from the motor itself. Thus, if any of the cards become caught above the pack, they will not be crushed since they simply act to support the slide member while the motor carries the cross head 17 downwardly under power.

The entire mechanism may be enclosed in a suitable ornamental housing 41.

The extreme outward position of the block 22 is limited by means of tie members 21. The downward movement of the gripping plate is likewise limited by means of a stop bar 20 which contacts the back of the slide 16.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A device for successively changing the foremost card of a pack of cards comprising: a card holder for supporting the pack at a rearwardly inclined angle; a vertically reciprocating member positioned at the rear of said card holder; frictional engaging means on said member for contacting the back of the rearmost card of the pack to elevate it above the remaining cards; gripping means for gripping the elevated card; and releasing means for releasing the gripping means when said card has been elevated above the pack.

2. A device for successively changing the foremost card of a pack of cards comprising: a card holder for supporting the pack at a rearwardly inclined angle; a vertically reciprocating member positioned at the rear of said card holder; frictional engaging means on said member for contacting the back of the rearmost card of the pack to elevate it above the remaining cards; a gripping member carried from said reciprocating member and positioned ahead of the rearmost card, said frictional member acting to force said card forwardly against said gripping member; and means for releasing said gripping member when said rearmost card has cleared the pack.

3. A device for successively changing the foremost card of a pack of cards comprising: a card holder for supporting the pack at a rearwardly in-

clined angle; a vertically reciprocating member positioned at the rear of said card holder; frictional engaging means on said member for contacting the back of the rearmost card of the pack to elevate it above the remaining cards; a gripping member carried from said reciprocating member and positioned ahead of the rearmost card, said frictional member acting to force said card forwardly against said gripping member; means for releasing said gripping member when said rearmost card has cleared the pack; a gripping lever hingedly supported from said reciprocating member and resting on said card; a downwardly projecting gripping block on said lever, said card being gripped between said friction member and said block; and stationary means contacted by said gripping lever to release said block from said card.

4. A device for successively changing the foremost card of a pack of cards comprising: a card holder for supporting a pack of cards at a rearwardly inclined angle; a vertical guide member positioned at the rear of said pack; a slide member vertically slidable on said guide member; a friction block; resilient means for supporting said friction block ahead of said slide member so that it will contact the back of the rearmost card as the slide rises; a gripping lever hinged to said slide member and extending forwardly over said card; a downward projection on said gripping plate for engaging the front of the rearmost card as the latter is elevated; and a releasing member positioned in the downward path of the gripping lever to release the latter from the card at a predetermined point in its travel.

5. A device for successively changing the foremost card of a pack of cards comprising: a card holder for supporting a pack of cards at a rearwardly inclined angle; a vertical guide member positioned at the rear of said pack; a slide member vertically slidable on said guide member; a friction block; resilient means for supporting said friction block ahead of said slide member so that it will contact the back of the rearmost card as the slide rises; a gripping lever hinged to said slide member and extending forwardly over said card; a downward projection on said gripping plate for engaging the front of the rearmost card as the latter is elevated; and a flexible spring blade positioned in the path of the gripping member to support the latter as said slide member moves downwardly so as to release said card.

6. A device for successively changing the foremost card of a pack of cards comprising: a card holder for supporting a pack of cards at a rearwardly inclined angle; a vertical guide member positioned at the rear of said pack; a slide member vertically slidable on said guide member; a friction block; resilient means for supporting said friction block ahead of said slide member so that it will contact the back of the rearmost card as the slide rises; a gripping lever hinged to said slide member and extending forwardly over said card; a downward projection on said gripping plate for engaging the front of the rearmost card as the latter is elevated; a releasing member positioned in the downward path of the gripping lever to release the latter from the card at a predetermined point in its travel; a cross head slidably mounted on the guide member below the slide member; and means for vertically reciprocating said cross head.

7. A device for successively changing the foremost card of a pack of cards comprising: a card holder for supporting the pack at a rearwardly in-

- inclined angle; a vertically reciprocating member positioned at the rear of said card holder; means on said member for gripping the rearmost card of the pack, elevating the latter and dropping the same on the front of the pack; a back plate in said card holder; and means for adjusting the position of the back plate to change the relative position of the rearmost card of the pack in relation to said gripping means.
- 5 8. A device for successively changing the foremost card of a pack of cards comprising: a card holder for supporting the pack at a rearwardly inclined angle; a vertically reciprocating member positioned at the rear of said card holder; means 10 on said member for gripping the rearmost card of the pack; means for releasing said rearmost card from said gripping member at a predetermined point in its travel; and an actuating lever extending forward of said card holder for raising 15 20 said reciprocating member.
9. A device for successively changing the foremost card of a pack of cards comprising: a card holder for supporting a pack of cards at a rearwardly inclined angle; a vertical guide member positioned at the rear of said pack; a slide member vertically slidable on said guide member; a friction block; resilient means for supporting said friction block ahead of said slide member so that it will contact the back of the rearmost card as the slide rises; a gripping lever hinged to said slide member and extending forwardly over said card; a downward projection on said gripping 10 15 20 plate for engaging the front of the rearmost card as the latter is elevated; a releasing member positioned in the downward path of the gripping lever to release the latter from the card at a predetermined point on its travel; a cross head slidably mounted on the guide member below the slide member; a motor; a rotary member driven from said motor; and a connecting rod extending from an eccentric position on said rotary member to said cross head for vertically reciprocating the latter.
